CLAIM

The ornamental design for a weight for percussion, as shown and described.

DESCRIPTION

FIG. 1 is a perspective view of the front, bottom and left side of a weight for percussion showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the design in use.

The broken lines illustrate the portions of the weight for percussion and the environmental structure that form no part of the claimed design.

1 Claim, 6 Drawing Sheets
